HINGE FOR DOOR CONSTRUCTION

Henry J. Siess, Detroit, Mich., assignor to Crawford Door Company, Detroit, Mich., a corporation of Michigan

Application May 13, 1940, Serial No. 334,720

5 Claims. (Cl. 16—171)

This invention relates to upward acting closures of the sectional type and more specifically relates to hinge devices having separable mating parts which can be mounted on the door panels or sections at the factory and interlocked "on the job" to provide an articulated door.

The invention will hereinafter be specifically described in connection with an upward acting garage door of the sectional type, but it should be understood that the invention is not limited to such use, and, in general, is adapted for connecting pairs of movable members in articulate relation.

Heretofore, sectional type garage doors had the sections thereof hinged together by means of permanently united hinge parts. This required a mounting of the hinges "on the job," since shipment of a full size articulate door was impractical. As a result, the door sections were assembled one by one from the bottom panel up, in the doorway, and the hinges were mounted on the thus positioned panels as the door sections were being built up. The mounting of the hinges on the vertical panels was a time-consuming and difficult operation.

The present invention now deals with hook type hinges having separable mating parts connecting the door sections in articulate relation. The hinge parts can be disengaged and mounted individually, at the factory, in operative position on each door section or panel. The panels can be shipped in individual relation with the hinge hardware thereon.

The hinges each have a pair of interlocking parts with one of the parts carrying a pin accommodating a roller which is engageable in tracks to guide the door sections. The door sections with the hinge parts thereon can be mounted successively in position in the doorway as is customary, but the sections are immediately interlocked into a single articulated door by the previously mounted hinges thereon. This avoids the heretofore necessary time-consuming and difficult operation of mounting the hinge hardware on the door sections as the same are being built up in the doorway.

The rollers carried by the hinges of this invention can be engaged in the vertical door tracks, and the tracks, with the rollers mounted therein, are then merely secured in position in the doorway.

It is, therefore, an object of this invention to provide an upward acting door construction of the sectional type including disengageable interlocking hinge parts adapted to be individually

mounted on the door sections and then readily interlocked for holding the door sections in articulate relation.

A further object of the invention is to provide an upward acting door construction of the sectional type including disengageable interlocking hinge parts holding the door sections in articulated relation and at the same time forming supports for guide rollers.

10 Another object of the invention is to provide hinges for connecting door sections in articulate relation while at the same time providing axes of rotation for guide rollers.

Another object of the invention is to provide 15 interfitting adjoining edges for closure sections which are shaped to hold the sections in a single plane throughout their widths while at the same time accommodating articulate movements of the sections.

20 A further and specific object of the invention is to provide hinges for closure members which are readily locked together during all normal articulate movements of the sections but which are also readily detachable from each other without the aid of tools.

Another specific object of the invention is to 25 provide hook type hinges for the side edges of sectional type doors which are locked in assembled relation in all normal operating positions of the door but which can be readily disengaged when the door sections are articulated through a greater angle than any operating angle.

30 A further specific object of the invention is to provide hook type hinges for sectional type doors which are locked together through a sleeve carrying a guide roller. Other and further objects of the invention will be apparent from the following detailed description of the annexed sheets of drawings which disclose preferred embodiments 35 of the invention.

On the drawings:

Figure 1 is a vertical cross-sectional view taken 40 transversely through an upward acting door of the sectional type equipped with interfitting door sections and hinges according to this invention.

Figure 2 is a fragmentary enlarged end elevational view of one of the door sections shown in Figure 1 and illustrating the female part of a hinge for connecting the door sections.

Figure 3 is a view similar to Figure 2 of an adjoining door section having the male part of the hinge secured thereon.

Figure 4 is a fragmentary front elevational view of the door sections of Figures 2 and 3 hav-

ing the hinge parts thereof mounted in interlocking relation.

Figure 5 is a vertical cross-sectional view, with parts in elevation, taken along the line V—V of Figure 4.

Figure 6 is a fragmentary enlarged vertical cross-sectional view taken along the line VI—VI of Figure 4.

Figure 7 is a fragmentary end elevational view of two adjoining door sections having modified hinge parts thereon and illustrating in dotted lines the manner in which the female hinge part is slipped onto the male hinge part.

Figure 8 is an isometric view illustrating the manner in which the door sections of Figure 7 can be built up into the complete door right in the doorway.

Figure 9 is an outside elevational view of the door sections and hinges shown in Figures 7 and 8, illustrating the manner in which the hinge parts are locked together in operative assembly.

Figure 10 is a plan view of the door section carrying the male hinge part shown in Figures 7, 8 and 9.

Figure 11 is a fragmentary end elevational view of a pair of door sections equipped with male and female hinge parts of a further modified design and illustrating, in dotted lines, the manner in which the female hinge part is mounted on the male hinge part.

Figure 12 is an outside elevational view of the door sections and hinge parts shown in Figure 11 illustrating the manner in which the hinge parts are locked together when the door sections are in a single plane.

Figure 13 is an end elevational view of the hinge parts and door sections shown in Figure 12.

Figure 14 is a top plan view of the door section and male hinge part illustrated in Figures 11, 12 and 13.

Figure 15 is a fragmentary end elevational view of a pair of adjoining door sections having hinge parts of a still further modified design mounted thereon and illustrating the manner in which the male hinge part is slipped into the female hinge part.

Figure 16 is a view similar to Figure 15 illustrating the interlocking of the hinge parts when the door sections are in a single vertical plane and also illustrating in dotted lines the maximum angular movement of the door sections in operating position to show that the hinge parts cannot become disengaged during operation of the door sections.

Figure 17 is a front plan view, with parts in vertical cross section, of the door sections and hinge parts shown in Figures 15 and 16 and also illustrating the manner in which the male hinge part carries a guide roller for the door sections.

Figure 18 is a fragmentary end elevational view of a pair of door sections equipped with a further modified form of interlocking hinge parts according to this invention and illustrating in dotted lines the maximum angle between the door sections encountered during normal operation of the door to show that the hinge parts cannot become disengaged during such operation.

Figure 19 is an outside plan view, with parts in vertical cross section, taken substantially along the line XIX—XIX of Figure 18.

As shown on the drawings:

In Figure 1 the reference numeral 10 designates generally a doorway of a building or garage defined by side door jambs such as 11, a lintel

12 and a floor or sill 13. The doorway 10 is closed by a sectional type door 14 composed of door sections 14a, 14b, 14c and 14d connected together for articulate movement and mounted on rollers 15 engageable in tracks such as 16. The tracks 16 extend vertically along the inside of the doorway from the sill to the lintel and then curve inwardly into the building to horizontal portions suspended from the ceiling or side walls of the building (not shown). The door 14 is thus mounted for vertical movement into and out of the doorway and for horizontal movement in an overhead position. The door in its fully opened position is disposed substantially horizontally along the horizontal track sections, and in its closed position is disposed vertically along the vertical track sections.

A spring-urged winding drum or sheave 17 is rotatably mounted on the lintel 12 of the doorway inside of the building by means of brackets such as 17a bolted to the lintel. A cable 18 extends from the sheave 17 along the outer face of the door 14 and is secured at 19 in the bottom door section 14a. The spring-urged sheave 17 serves to wind up the cable 18 for counterbalancing the weight of the door to facilitate movement thereof from vertical closed position to horizontal overhead position. An unwinding of the cable from the sheave permits the door to close while at the same time movement of the door into a closed position winds up the spring to resist the gravity action of the weight of the door and to prepare the spring for the next opening operation.

As shown in Figures 2, 4 and 5, alternate door sections such as 14b have their side edges equipped with metal hinge parts such as 20. These hinge parts 20 include an angle plate having one leg 21 thereof extending over the inner broad face of the door sections and bolted to the door sections by means of bolts 22. The other leg 23 of the angle plate extends over the side edge of the door sections. This leg has an offset apertured portion 24 in spaced relation from the side edge of the door and extending beyond the bottom edge of the door sections. The offset portion 24 has a circular recess 25 therein communicating through the bottom edge thereof by a vertical slot 26.

The other alternate door sections such as 14a and 14c carry the male hinge part 27 composed of an angle plate having one leg 28 thereof extending over the inner broad face of the door sections and bolted to the sections by means of bolts

29. The other leg 30 of the plate extends over the side edge of the door sections as shown and has a free end portion 31 slightly offset from the door edge as shown in Figure 4 and extending beyond the top of the door sections. This free end 31 has a pin 32 extending therethrough with the head 32a of the pin disposed between the door sections 14a and 14b and the inner face of the offset portion 31. The pin 32 is fixedly mounted in the offset portion and projects laterally from the side edge of the door section. As shown in Figures 4 and 5, the axis of the pin 32 is about in line with the adjoining ends of the door sections.

The pin 32 is adapted to fit through the slot 26 in the female hinge member 20 so that the door section 14b can be assembled on the door section 14a.

The roller 15 is mounted on a sleeve 33 adapted to fit over the pin 32 and rotate therearound with the roller. The outside diameter of the sleeve 33

is larger than the slot 26 in the female member so that the assembly of the sleeve on the pin within the circular recess 25 locks the male and female hinge parts together in articulate relation.

The door 14 can thus be built up from the sections 14a and 14b right in the doorway 10 by merely mounting the bottom door section 14a with its male hinge part thereon in position in the doorway against the door jambs 11. The succeeding sections are then built up on top of the section 14a by merely slipping the female hinge part over the pins of the male hinge part and by inserting the roller sleeve 33 over the pin to lock the hinge parts together. The rollers 15 are seated in the tracks 16 and the tracks are secured in position in the doorway. The assembly of the door is complete without previous assembly of the door sections out of the doorway or without necessity for mounting the door hinges on the sections in the doorway.

As shown in Figure 6, adjoining door sections such as 14a and 14b have their adjacent ends rabbeted for interfitting relation. Thus the door section 14a has a rounded bead portion 34 projecting upwardly therefrom between the broad faces thereof. The rounded bead portion 34 terminates in an abutment surface 35 parallel with the inner broad face of the section but spaced inwardly from this broad face. The other end of the bead terminates in a flat shoulder 36 normal to the outer broad face of the door. The inner face of the door section 14a is beveled as at 37 so that the abutment surface 35 has an inclined cut-out portion or bevel 37 therebeneath. The abutment surface 35 is offset from the shoulder 36.

The adjoining door section 14b has a rounded recess 38 receiving the bead 34. The recess 38 is bounded by a finger 39 having an abutment surface 40 contacting the surface 35 when the door sections are in a single plane. The other side of the recess terminates in a finger 41 having an end 42 adapted to seat on the shoulder 36. The recess 38 is at a different curvature than the curvature of the bead 34 so that the bead is not in full contact with the recessed surface. The bottom of the finger 39 is above the bottom of the finger 41 and is beveled upwardly as at 43. Thus when the door sections are in a single plane a notch is formed along the inner broad faces thereof while the outer broad faces are flush. The door sections are adapted for articulate movement since the finger 41 can ride over the bead 34 while the beveled surface 43 can move toward the beveled surface 37. Contact between the recess 38 and the bead 34 will be progressive as illustrated in dotted lines.

The fingers 39 and 41 together with their abutting surfaces hold the door sections along their entire lengths to prevent buckling thereof and when the door sections are in a single plane, a sealed effect is obtained without the aid of weatherstrips.

The bead 34 is not intended as a hinge part but is merely provided to fit into the recess 38 for holding the door sections in alignment along their entire lengths. The metal hinge parts described above take the load and the wood parts are not subjected to wearing action.

In Figures 7, 8, 9 and 10 the door sections 14a and 14b are equipped with a modified form of interlocking hinge part according to this invention. In these figures parts substantially identical with parts described in connection with

Figures 1 to 6 have been marked with the same reference numeral.

In Figures 7 to 10 the door section 14b carries a female hinge part 40 composed of an angle plate member having one leg 41 thereof extending over the inner face of the door section and bolted thereto by means of bolts 42 while the other leg 43 thereof extends over the side edge of the door. The leg 43 has an offset free end portion 44 extending beyond the bottom of the door section and provided with a circular recess 45. The recess 45 has a slot 46 extending therefrom through the inner edge of the free end portion 44. The slot 46 is of less width than the diameter of the recess 45. The slot 46 differs from the slot 26 illustrated in Figures 2 to 4 in that it extends through the inner edge of the female hinge portion instead of through the bottom edge.

The male hinge portion 47 on the door section 14a is composed of an angle plate having one leg 48 thereof extending over the inner face of the door section and bolted thereto by means of bolts 49 while the other leg 50 thereof extends over the side edge of the section. As shown in Figure 10, the legs 48 and 50 are preferably connected through a rounded portion 51 to prevent a right angle bend between the parts and thus increase the strength of the plate.

The leg 50 has a free end portion 50a carrying a pin 52 which projects therethrough and extends laterally from the side edges of the door section about in line with the mating ends thereof. The pin 52 is cylindrical for a major portion of its length but has a portion 53 of reduced size adapted to fit through the slot 46 of the female member. This reduced portion is inclined to the broad faces of the door section 14a as illustrated in Figure 7 at an angle such that the slot 46 of the female portion 40 can never be aligned therewith when seated in the recess 45 during normal articulated movements of the door sections in operative position.

However, as illustrated in dotted lines in Figure 7, the female hinge part is adapted to be slipped over the reduced portion 53 of the male pin when the door section 14b is at a greater angle than that reached by normal operation of the door. Then when the door sections are mounted in operative position, the hinge parts are permanently locked. Each pin 52 can carry a roller 15 engageable in the tracks 16.

As illustrated in Figure 8, the door can be built up from the sections thereof in the doorway by mounting the sections step by step to bring their hinge parts into interlocking relation. The movement of the door sections from vertical to horizontal position is such that the same never reach an angle as great as that illustrated in Figure 7 for assembling the sections together.

In Figures 11 to 14 there is illustrated a still further modified interlocking hinge for the door sections 14a and 14b. In these figures, the reference numeral 60 designates generally the female hinge part composed of an angle plate having a leg 61 bolted to the inner broad face of the door section 14b by means of bolts 62 and a second leg 63 disposed over the side edge of the door section 14b. The leg 63 has a free end hook portion 64 projecting therefrom and beyond the end of the door section 14b. As shown in Figure 12, this hook portion 64 is slightly offset from the leg 63 so as to be in spaced relation from the door section.

The male hinge part 65 is mounted on the door

section 14a and consists of an angle plate having one leg 66 thereof bolted to the inner face of the door section by means of bolts 67 with the other leg 68 thereof extending over the side edge of the door. The leg 68 has a free end portion 69 projecting beyond the end of the door section 14a and carrying a pin 70 extending laterally from the door section. A flange 71 is turned outwardly from the end portion 69 as shown.

As illustrated in Figure 11, the hook 64 of the female hinge section 60 is adapted to be slipped over the pin 70 of the male section 65 when the door sections 14a and 14b are disposed in an angular relationship greater than that assumed during the normal operation of the door. The hook 64, however, will engage the flange 71 on all normal articulated movements of the door sections and this flange will hold the hook on the pin to maintain the hinge parts in interlocking relation.

The door can be built up in position from the door sections in the same manner illustrated and described hereinabove.

The pin 70 receives a roller such as 15 thereover to guide the door sections in the tracks.

Another embodiment of the invention is illustrated in Figures 15, 16 and 17. In these figures the door sections 14a and 14b carry the male and female hinge parts in reverse relationship. In other words the door section 14b carries the male hinge part which is slipped into the female hinge part when the sections are substantially at right angles but which is held in the female part during all normal angular movements of the door sections in operation. The female hinge part has a hook member adapted to receive the pin only when the parts are at least in right-angular relationship and retaining the pin in all other angles greater than right angle relationship.

In Figures 15 to 17 the door section 14a carries the female hinge part 80 composed of an angle plate having one leg 81 thereof bolted to the inner face of the door section by means of bolts 82 and the other leg 83 thereof extending over the side edge of the door and having a free end portion 84 extending beyond the end of the door section. This free end portion 84 has a recess 85 therein opening toward the inner face of the door section along a downwardly inclined path. As illustrated in Figure 17, the free end portion 84 is offset from the side edges of the door sections 14a and 14b.

The door section 14b carries the male hinge part 86 composed of an angle plate having one leg 87 thereof extending over the inner face of the section and bolted thereto by means of bolts 88 while the other leg 89 thereof extends over the side edge of the door.

The leg 89 has a free end portion 90 adapted to fit between the end portion 84 of the female section and the side edges of the door sections as illustrated in Figure 17. The free end portion 90 is offset slightly from the edges of the door sections to accommodate the head 91a of a pin 91 extending therethrough. The pin 91 projects laterally from the side edges of the door and is adapted to receive the sleeve 33 of the roller 15 in rotatable relation therearound.

The pin 90 is inserted in the recess 85 of the female hinge part 80 only when the door sections are in the angular relationship shown in Figure 15. When the door sections are mounted in operative position in a doorway, the same never assume an angular relationship greater than that shown in dotted lines in Figure 16 so that

the pin 91 cannot be removed from the recess 85 because the recess opens downwardly and requires a greater angular relationship between the door sections to permit removal of the pin.

- 5 In the further modification shown in Figures 18 and 19, the door section 14b carries a female hinge part 100 composed of an angle plate having a leg 101 bolted to the inner face of the door by means of bolts 102 and a second leg 103 extending over the side edge of the door. The leg 103 has a free end section 104 terminating short of the bottom end of the door section and turned outwardly and inwardly, as best shown in Figure 19, to provide a segmental annular recess 105.
- 15 The door section 14a carries the male hinge part 106 composed of an angle plate having one leg 107 thereof extending over the inner face of the door section and bolted to the section by means of bolts 108 and a second leg portion 109 extending over the side edge of the door section. The leg 109 is provided with a slightly offset free end portion 110 extending beyond the top end of the door section 14a and carrying a laterally projecting pin 111. As shown in Figure 19, the pin 111 extends through the free end portion 110 and has a head portion 111a disposed between the door sections and the free end portion.

The top end of the free end portion 110 has a segmental annular flange 112 adapted to be seated in the recess 105 of the female member for holding the door sections together in articulated relation.

The flange 112 is adapted to be guided into the recess 105 by disposing the door section 14b in right-angular relationship with the section 14a. The flange 112 can slide in the recess 105 to permit articulate movements of the door sections and will not be removed from the recess during normal operating movements of the door sections since, as shown in Figure 18, in dotted lines, the door section 14b does not assume an angular relationship relative to the door section 14a that is great enough to permit removal of the flange. However, the hinge parts are readily connected and the sectional door can be built up in the doorway from the door sections in the manner illustrated in Figure 8.

The pin 111 is adapted to receive the roller 15 and sleeve 33 thereon in the same manner illustrated in Figure 17.

From the above descriptions it should be understood that this invention now provides for the building up of articulated sectional type doors in place in a doorway through the medium of interlocking hinges containing male and female parts which are readily assembled and which, when assembled, will not permit separation of the door sections during any angular movements thereof occurring in operation of the door. The hinges provided by this invention carry pins which support rollers for guiding the sectional type door into and out of position in the doorway. The pins and rollers extend laterally from the side edges of the door sections.

65 The hinge parts of this invention are securely united to the door sections and have flanges overlapping the inner face of the sections so that securing means can enter transversely into the door sections thus affording a stronger connection than is possible by merely screwing hinge plates onto the side edges of the door.

It will, of course, be understood that various details of construction may be varied through a wide range without departing from the principles of this invention and it is, therefore, not the

purpose to limit the patent granted hereon otherwise than necessitated by the scope of the appended claims.

I claim as my invention:

1. In an upward acting door construction including a pair of door sections, the improvements which comprise a female hinge part disposed over a side edge of one of said door sections and having an offset recessed free end portion, a second hinge part disposed over the side edge of the second door section, a pin projecting laterally from said second hinge part adapted to be seated in the recess of the first hinged part, and a guide roller having a hollow stem disposed over said pin and through said recess to hold the hinge parts together in pivotal relation.

2. A hinge construction adapted for uniting the door sections of upward acting doors comprising male and female angle plates each having legs adapted to be secured to the broad faces of door sections and other legs adapted to be disposed over the side edges of the door sections, a pin projecting laterally from one of said hinge parts, the other of said hinge parts having a recess adapted to receive said pin, and a sleeve member adapted to be disposed over said pin and through said recess to hold the hinge part in pivotal relation.

3. A hinge comprising a male part having a pintle fixed thereon, a female part having a pintle receiving recess therein communicating with an edge of the part to provide an entrance gap in said edge for receiving the pintle therethrough, said gap being narrower than said recess, and a sleeve sized too large to pass through said gap adapted to be mounted on the pintle and project into said recess for retaining the pintle in the recess to articulate connect the hinge parts.

4. A hinge adapted for uniting the door sections of upward acting doors comprising male and female angle plates each having legs adapted to be secured to the broad faces of door sections and other legs adapted to be disposed over the side edges of the door sections, each of said other legs having overlappable free end portions, a pintle secured on and projecting normally from said free end of the male hinge part, said free end of the female hinge part being bifurcated and having a recess of greater diameter than the space between the furcations thereof communicating with said space, said pintle on the male part adapted to pass between said furcations into said recess, and a hubbed roller for mounting the door sections having the hub thereof slidably carried by said pintle and sized to project snugly into said recess of the female hinge part for retaining the pintle therein and thereby articulate connect the hinge parts.
5. A hinge construction adapted for uniting adjoining door sections of a sectional door construction having guide tracks adjacent the side edges of the door sections, said hinge construction comprising a pair of separable hinge parts on the side edges of said adjoining door sections, said hinge parts having end portions in overlapping assembled relation, a pin on one end portion projecting laterally therefrom between the inner and outer faces of the door sections, said other end portion having a recess adapted to receive said pin in pivotal relation, and a roller movable in said track having a hub mounted on the pin to mount the door sections in operative relation to the track.

HENRY J. SIESS.
